LADY'S GARMENT

Audrey Cross Bishop, Seattle, Wash., assignor of
one-half to Lilas M. Blodgett, Seattle, Wash.

Application November 24, 1943, Serial No. 511,527

8 Claims. (Cl. 2—73)

1

My invention relates to a lady's garment, and more particularly to a garment such as a slip, a nightdress, or the like.

Two of the principal factors which determine the marketability of such garments is their fit and the economy with which they can be manufactured. By constructing such garments according to my invention both proper fit and economy of fabrication are achieved, while at the same time the garment is of pleasing appearance.

It is well known that woven material can stretch on the bias in conformity with the body contours, to fit snugly. On the contrary, the weave of the material in portions of the garment which are stressed considerably should be arranged so that one group of threads is aligned with the direction of principal stress, to resist in tension the forces to which that part of the garment is subjected.

A sleeveless and legless body garment, such as a lady's slip, is subjected to appreciable stress only in one part, and under only one type of body movement. That part is the lower back portion of the garment, which is stressed when the wearer bends forward or is seated. Consequently it is desirable for the weave of the cloth forming this portion of the garment to have its threads extending respectively vertically and circumferentially of the person.

On the other hand, in order to produce a garment of the general type here under consideration which fits closely about the waist, back and bosom of the wearer, the material covering these parts should be on the bias. In addition the side and front portions of the skirt should be on the bias, or substantially so, so that the material may drape gracefully from the relatively small dimension at the waist to the considerably greater dimension at the lower edge of the skirt, if it is sufficiently full to afford ample freedom of movement in walking. A further reason for the material at the waist of the garment being on the bias is to enable this portion to stretch circumferentially, accompanied by lengthwise shortening of the garment, while it is being put on, and after the garment is in place on the wearer to contract circumferentially and to be extended in length.

Economy in manufacture of such a garment can be promoted by saving in material and by saving in labor. Sewing the seams of the garment is the major labor factor, so that any reduction in the aggregate length of the seams required is desirable. Usually reducing the number of pieces

5 forming the garment will contribute toward such result. In general, a garment made of fewer pieces is also neater in appearance. No advantage is gained by the saving in labor effected by reducing the number of pieces, however, if such expedient causes a greater waste of material.

10 Heretofore, to the best of my knowledge, ladies' slips and similar garments have not been made with the weave of the material on the bias, or substantially so, in the bosom portion and in the front and side portions of the skirt, and with the weave of the material on the straight in the back of the skirt, while at the same time fitting smoothly and snugly around the waist. It is a 15 principal object of my invention to arrange the weave of the material in this manner, in a lady's slip or comparable garment while at the same time constructing the garment so that it fits the body correctly. Such a garment will shape it- 20 self readily to the body contours of the wearer, yet its life will be increased, and it will be inclined to hold its shape better after being worn than previously available garments.

25 A further important object of my invention is to fabricate such a slip or the like from a minimum number of pieces of material, only two being required, thus greatly reducing the work involved in assembling the pieces, while a more attractive garment results. In accomplishing such 30 object no more scrap material is produced in cutting the pieces of the garment from the cloth stock than occurs in making such garments according to conventional practice. On the contrary, a garment constructed according to my 35 invention can be made from considerably less material than is usually needed for a similar conventional garment of equal size.

40 More specifically it is an object to make the entire skirt and the bosom of the garment of a single piece of cloth, the weave of which extends in the most desirable directions in the various parts as mentioned above, and to make the upper portion of the back and central portions of the sides, extending around to the front of the 45 garment, of another piece of material having its weave on the bias.

50 Still another object of the invention is to arrange the contour of the seam between the two pieces which form the garment to facilitate proper fitting over critical portions of the body, particularly beneath the bust and around the waist. Such seam does not reinforce the waist portion of the garment in a manner to resist its stretching while the garment is being put on. The various seams will, however, provide additional strength

where most desirable. Moreover the contour of the pieces is such that for the most part the weave of the material on opposite sides of the seams is directed similarly, so that bias material is joined to bias material.

Additional objects of my invention will be appreciated after considering the following particular description of my garment. It will be understood that various details of its construction can be modified to a greater or less degree while still employing its principal features.

Figure 1 is a front perspective view of a slip embodying my invention, while Figure 2 is a side elevation view, and Figure 3 is a rear elevation view of the slip.

Figure 4 is a plan view of the two panels of cloth constituting the blank employed in fabricating the slip, illustrating the relationship of such panels to a piece of material from which they have been cut.

In making ladies' garments, such as a slip, it has been recognized that the weave of the material from which the bosom portion is made should be on the bias in order to fit close to the body. A cylindrical band of material with its weave thus directed is not sufficiently flexible to fit correctly, and it has been considered necessary for that reason to form even the upper portion of the garment of several pieces.

The skirt portion of a slip also has been made of several pieces. Some manufacturers prefer the weave of the material forming the skirt to be disposed vertically, but a cylinder of cloth with this weave direction is not satisfactory because, if it were made large enough so that the skirt bottom has sufficient freedom of movement, there would be far too much material at the waist. On the other hand, some manufacturers prefer that the material be on the bias, which enables the skirt to fit and drape better than when the material is on the straight, but a single piece of material of the size required for a skirt cannot be cut from cloth stock of widths usually available when the weave runs on the bias.

It has therefore, prior to my invention, been considered to be impossible to construct a properly fitting slip of a few pieces of material, and at least four, and frequently more, separate pieces have been joined together to make slips.

An important feature in the fabrication of my slip is the formation, from a single piece 1, of the entire skirt of the garment 10, 11, 12, the front of the bosom portion 13, and the front part of the garment at the waist 14, in which the weave is on a true bias for the entire area of the bosom, the waist front and the skirt front portions. It is approximately on the bias for the side portions 11 of the skirt, and is on the straight for the skirt rear portions 12. Such direction of the weave is accomplished by cutting the blank 1 for this piece from cloth stock in the manner indicated in Figure 4. The front center line of the garment is placed on the cloth at 45 degrees to its threads, that is, on a true bias.

Since the bottom of the skirt must be considerably longer in circumference than the top of the skirt in order to fit the wearer properly, both of these lines are generally arcuate. Whenever possible a skirt with adequate fullness is desired, and this can be achieved by making the skirt portion of the blank in the form of an arcuate band, which in the present instance forms an integral part of a panel of substantially quadrant shape. When its front center line is on a true bias, therefore, each radial edge of the skirt

band will be parallel to a group of threads of the material, but one edge of the panel will be parallel to the warp threads, and the other parallel to the woof threads. When the lateral edges of the skirt blank are joined together by a vertical seam medially of the skirt back, as shown in Figure 3, the weave of the material in the portions 12 on both sides of this seam will be on the straight.

Several advantages are obtained by fabrication of the skirt in this manner. Only a single seam 15 is required, and it extends down the center of the skirt back, where it is not noticeable, whereas side seams passing downward across the hips may appear as ridges beneath a tight-fitting dress. Despite the generous allowance of material in the skirt it will drape in folds close to the figure because of the stretchability of the material on the bias in its sides 11 and front 10. The lower edge of the skirt therefore will not flare forward or laterally of the wearer, and it will fit smoothly at the side over the hip contour. The back of the skirt, however, despite the stretching stress to which it is subjected when the wearer stoops forward or sits down, will hang straight and will not bulge or sag, because it is reinforced both by the straight weave of the material in portions 12, and by the strengthening effect of the seam 15 itself. The skirt portion of the garment, therefore, has all the advantages of proper fit of a bias skirt without the attendant disadvantages.

The bosom portion 13 of the slip may stretch circumferentially as necessary to fit the bust, because it is on a true bias, and the points extending upwardly in front of the shoulders, and portion 1 at the waist, will fit snugly. The lower edges of the bosom portion 13 may be gathered or tucked at each side of the waist front portion 14 interconnecting the bosom and skirt portions, as indicated at 16, to draw the slip in to fit beneath the bust.

The slip is completed by a second panel 2 of the blank the center line of which is also directed diagonally of the threads of the cloth stock, as indicated in Figure 4, so that all the material in this element of the blank will be on a true bias. This panel is complementary to panel 1, completing the slip blank and forms the upper back portion of the slip and a waist yoke extending forward around the sides to its front. The contours of these panels may, of course, be varied, but several advantages are secured by shaping them approximately as illustrated in the drawings.

Preferably the lower edge 17 of the bosom or bodice front portion 13 at opposite sides curves from the waist front portion 14 rearwardly and upwardly to the upper edge of the garment, as may be seen in Fig. 2. The portions of such edge at the front and sides are spaced a substantial distance from the upper edge 18 of the skirt part at the waist above its side portions 11 so that the waist front portion takes the form of a vertically extending band of substantial length, as shown in Fig. 1. A notch of considerable width is thus formed between these edges 17 and 18 at each side of the portion 14 interconnecting the bosom and skirt parts. The edges 17 lie close beneath the bust, while the opposite ends of the upper skirt edge 18 curve rearwardly and downwardly around the waist, just above the hips, as shown best in Figure 2.

Panel 2, in addition to forming the upper portion of the slip or bodice back, has a waist yoke including tabs 20 extending from the rear of the slip forward into the notches at opposite sides of

the waist front band 14. The ends of these tabs are vertically coextensive with the length of this band and are joined to its opposite edges by generally vertical seams. It will be obvious that these tabs and the back piece, forming the waist yoke, may be sufficiently short so that, when the opposite sides of the waist front portion 14 are joined to such tabs 20, the waist portion of the slip will be held inward close to the body. This back piece 2 with its side tabs is designated a yoke because it supports the skirt portion of the slip and is responsible for the proper fit of the garment at the waist even though it is not necessary to gather the upper portion of the skirt. Such fitting is possible without undesired folds occurring in the material, because, as indicated, all the material at the waist is on the bias, and the excess fullness which would otherwise be present is removed by providing the notches in the radial edges of panel 1 which receive the tabs 20 of panel 2.

The upper edges 19 of the skirt back portions 12 are curved downward even more sharply than the upper edges of the skirt side portions 11. When these back portions are joined together by seam 15, therefore, a pronounced angle is formed by and between edges 19. The lower edge of panel 2 is the shape of a ceratoid cusp, forming a point 21, which fits in the angle between edge portions 19 of the skirt back as shown in Figure 3. This point, it will be noted, projects downward well below the waist of the garment, which is the portion of smallest circumference, as is apparent in Figure 2. When in the form of the blank the lower edge of panel 2 at opposite sides of this point is curved more sharply concave than the convexity of the upper skirt edge 18 and 19, as shown in Fig. 4. The seam joining the lower portion of panel 2 to the upper edge of the skirt is therefore of considerably greater length than the minimum circumference of the garment. Consequently this seam does not constitute a troublesome constriction when the slip is being put on, for the waist portion, which is smallest in circumference, may stretch because the cloth is on the bias throughout this region, and the point 21 will be pulled upward to allow such expansion. When the garment is in place on the wearer, however, the weight of the skirt will draw the seam downward again into the position illustrated.

It is to be noted that the thread directions are parallel, or very nearly so, on opposite sides of the seam joining the panels 1 and 2 throughout almost its entire length. Such disposition of the threads facilitates the formation of an even and smooth seam. Similarly, down the back of the skirt in each of the two parts 12, joined by seam 15, the weave is on the straight.

In a garment constructed as described above it will be seen that the length of the slip is not necessarily limited by the width of the material, since for longer than average garments an additional piece may be employed to fill out one corner of that back portion 12 which extends transversely of the material. Moreover the contour of the upper edge of the slip may be varied as desired. For wear beneath a dress cut low in the back it is merely necessary to notch the upper edge of panel 2, as may be required. Alternatively this single back panel could be replaced by two pieces each incorporating a tab 20, but usually this will not be necessary, and is not considered preferable.

Ordinarily the length of the slip and the waist

measurement bear a reasonably close relationship. The location of the waist may be altered readily merely by varying the proportions of bosom length to skirt length and similarly altering the position of tabs 20 of blank 2. The waist circumference may be decreased by cutting back the edge portions 12 of the skirt quadrant and shortening panel 2 circumferentially. While such operation will also decrease the peripheral length of the skirt bottom, this is not objectionable for a person having a small waist. Conversely, the waist measurement may be increased by extending the back portions 12 without the necessity of adding an insert, if the material stock is wide enough so that the slip skirt can be of sufficient length, and lengthening panel 2 circumferentially.

For a long-waisted person the waist front band 14 may be made longer by spacing the bosom lower edge 17 farther from the skirt upper edge 18, and correspondingly increasing the width of tabs 20. For such variation usually the edge 17 is raised and the edge 18 lowered, the extent of each alteration depending upon the particular location of the wearer's waist. Conversely, for short-waisted persons the edges 17 and 18 may be located closer together, but even in such case they will be spaced apart a substantial distance. The controlling factor in each case, as previously mentioned, is that the edges 17 curve upwardly and rearwardly immediately beneath the bust, while the edge portions 18 pass around the waist, curving increasingly rearwardly and downwardly immediately over the hips and merging with edges 19, to enable the garment to be fitted to best advantage. The shape of the blank used in the fabrication of my slip can thus be altered readily to fit precisely a particular wearer without changing the general quadrant shape of the blank. Since the weave of all the central parts is on the bias, however, the garment will fit well even though it may not be proportioned exactly for the individual figure.

It will be evident that cutting of the panels 1 and 2 can be facilitated, if desired, by folding the pattern and the cloth stock diagonally, and cutting the opposite side edges simultaneously, since each blank is symmetrical about its vertical center line. In many cases only about half as much material will be needed for making a slip of the construction described than is used for most slips of conventional types. After the panels are joined together in the manner described the slip may be completed by adding shoulder strips 3, as is customary. The same procedure as described above would, of course, be followed for making a nightdress or similar garment as for making a slip.

I claim as my invention:

1. A lady's garment, such as a slip or the like, comprising two pieces joined together in edge relationship, one piece forming the bosom part and having its lower edge curving from the front of the garment upwardly and rearwardly at opposite sides, further forming a skirt part having the opposite ends of its upper edge curving downwardly and rearwardly from the waist line of the garment, and also forming a vertically extending waist front band of substantial length integrally interconnecting the skirt and bosom portions, the two upright ends of the skirt part being joined by a seam extending centrally down the back, and a second piece forming the upper back part of the garment and a waist yoke intermediate the skirt part and the bosom part, and having ends

vertically coextensive with the length of said waist front band and joined to the opposite edges thereof.

2. The garment defined in claim 1, the opposite ends of the skirt part upper edge converging downwardly to define an angle having its apex at the seam joining the skirt part ends, and the second piece having a lower edge centrally pointed in the form of a ceratoid cusp and fitted into such angle between the opposite ends of the upper edge of the skirt part and joined to such ends.

3. A lady's garment, such as a slip or the like, consisting of only two pieces joined together in edge relationship, one piece forming the bosom part and having its lower edge curving from the front of the garment upwardly and rearwardly at opposite sides, further forming the entire skirt part having its upper edge curving from the front of the garment at the waist rearwardly and downwardly at opposite sides, and also forming a vertically extending waist front band of substantial length integrally interconnecting the skirt and bosom portions, the weave of the entire bosom part, the entire waist front band, and the front portion of the skirt part being on the bias, and the weave of the back portion of the skirt part being on the straight, the two upright ends of the skirt part being joined by a seam extending centrally down the back, and a second piece having its weave entirely on the bias and forming the upper back part of the garment and a waist yoke intermediate the skirt part and the bosom part, and having ends vertically coextensive with the length of said waist front band and joined to the opposite edges thereof.

4. A lady's garment, such as a slip or the like, comprising a skirt portion, a bosom portion, a waist front portion interconnecting the skirt and bosom portions, and a waist yoke extending across the back and around the sides to the front of the garment and there terminating in tabs, said tabs being joined to said bosom portion, said waist front portion and the front part of said skirt portion, the lower back edge of said waist yoke having a central portion projecting downward a substantial distance below said tabs of the waist yoke, and the back part of said skirt portion having a notched upper edge receiving and joined in edge relationship to such downwardly projecting portion of said yoke.

5. A blank for a lady's garment, such as a slip or the like, comprising a panel of substantially quadrant shape adapted to form a skirt portion and a bosom portion and having corresponding notches of substantial width extending inward from the opposite radial edges thereof between said skirt and bosom portions, to define a radially extending waist front band therebetween of substantial length interconnecting the skirt and bosom portions, the upper edge of said skirt portion formed by said notches at opposite sides of said waist front portion being somewhat convex, and a second panel adapted to form an upper back portion and a waist yoke, having end tabs adapted for reception in the notches of said first panel and having a lower edge in the shape of a ceratoid cusp, the curved portions of such lower edge being concavely curved more sharply than the convex curvature of the upper edges of the skirt portion of said first panel but of a length

substantially equal to such skirt portion upper edges and adapted to be joined thereto.

5 6. A lady's garment, such as a slip or the like, comprising only a single piece forming substantially the entire bosom, the skirt front and the skirt back of the garment, and an upper back portion of the garment, said single piece being joined to said upper back portion by a seam extending from the front of the garment below the bosom portion rearwardly around the waist of the garment and downwardly to a location at the central portion of the back a substantial distance below the location of said seam at the front of the garment and below the garment waist.

15 7. A lady's garment, such as a slip or the like, comprising a bodice portion and a skirt portion, the front portion of the bodice and of the skirt both being on the bias, the back of the bodice portion being on the bias, and the back of the skirt portion being on the straight, said bodice and skirt portions being joined by a seam extending around the major portion of the garment from the waist portion of the garment at the front and below the bodice portion rearwardly and downwardly to a location at the central portion of the back a substantial distance below the location of said seam at the front of the garment and below the garment waist.

20 8. In a lady's garment, such as a slip or the like, a waist portion having a lower edge spaced a substantial distance downward from its upper edge, such lower edge extending rearwardly from the garment front and curved concavely from the sides of the garment, substantially at its natural waistline, downwardly and rearwardly to form at the back of the garment and below its natural waistline a downward projection in the shape of a ceratoid cusp, and a skirt portion including sides having upper edges substantially at the garment's natural waistline and a back having an upper edge curving downwardly from and in continuity with the upper edges of the sides, and being centrally notched below the garment's natural waistline complementary to and receiving 25 the ceratoid cusp downward projection of said waist portion, said lower edge of the waist portion and said upper edge of the skirt portion being joined in edge relationship around the sides and across the back of the garment by a seam 30 of a length substantially longer than the circumferential extent of the garment around the corresponding portion of the garment's natural waistline girth.

AUDREY CROSS BISHOP.
